PHONOGRAPH

Louis Z. La Forest, Orange, N. J., assignor to
 Thomas A. Edison, Incorporated, West Orange,
 N. J., a corporation of New Jersey

Application December 3, 1937, Serial No. 177,856

25 Claims. (Cl. 274—2)

This invention relates to phonographs and more particularly to an improved form of a closely fitting cabinet for a commercial phonograph.

It is desirable that cabinets for commercial phonographs be made small so that they may be suitably used on the desk of the operator with a pleasing appearance and with ease of portability. In order that such cabinets may fully protect the phonograph it is important that the phonograph be completely enclosed. Whenever a phonograph is completely enclosed by a closely fitting cabinet there are encountered difficulties in providing a suitable cover which will expose the phonograph for convenient operation. This is particularly difficult with the usual form of commercial phonograph which is so arranged that it must be accessible at its front and side portions for manipulation thereof whenever it is to be used. Access to the side portion is necessary for the purpose of mounting a record on a suitable record support, or mandrel, and for removing a record therefrom. Access to the front of the machine is necessary in order to operate a translating device which moves longitudinally of the mandrel and is adjustable by means of a control lever commonly provided therewith. In closely fitting cabinets for such machines there may be provided a cover for the front portion of the phonograph and a separate closure member for the side portion. The cover may then be of small and convenient form, and by a novel hinging arrangement it may be moved to a convenient open position closely fitting the cabinet. Moreover, by suitable means coupling the cover with the side closure member the operation of the cover between its open and closed positions may be made to operate the side closure member between its respective open and closed positions.

With such a novel cabinet structure closely fitting the phonograph there may be secured other benefits by which the operation of the phonograph is safeguarded. The translating devices in commercial phonographs are adjustable, by means of the aforesaid control lever, to respective operative positions wherein it engages the record for recording thereon and reproducing therefrom. This control lever is also adjustable to a neutral or an inoperative position wherein the translating device is disengaged from the record. It is of primary importance that the control lever be in its inoperative position whenever a record is mounted on, or removed from the mandrel, as a safeguard against damage to delicate parts of the translating device and to the record surface. Such a safeguard may very

conveniently be in the form of the movable side closure member provided for closing the side portion of the phonograph, and for the convenient operation of the machine, it may be operated by the control lever to suitable positions for maintaining the mandrel inaccessible for operation except when the control lever is in an inoperative position.

It is therefore an object of my invention to provide a cabinet completely enclosing and closely fitting a phonograph without sacrificing the ease of operation of the phonograph.

It is another object to provide means, in the form of a cabinet for a phonograph, for maintaining the correct sequence of adjustments in the operation of a phonograph.

It is another object to provide a small and conveniently arranged cabinet for supporting a phonograph and safeguarding its operation.

It is another object to provide, for a commercial phonograph, a cabinet having a plurality of closure members, operatively connected to each other and to a primary control means of the phonograph, for protecting the phonograph during its operation.

It is another object to provide a novel structure arrangement for a phonograph cabinet whereby the appearance of the cabinet is enhanced and the phonograph is readily accessible for servicing or repairs.

It is a still further object to provide a construction for a phonograph cabinet which may be easily assembled and disassembled.

Other and allied objects will more fully appear from the following description and the appended claims.

In the description of my invention reference is had to the accompanying figures, of which:

Figure 1 is a perspective view of a phonograph cabinet according to my invention showing the cover in open position, the phonograph control lever in a forward operative position, and the side closure member in an intermediate position.

Figure 2 is a side elevational view of the cabinet of my invention showing the cover and side closure member in their respective open positions.

Figure 3 is a fragmentary side elevational view, with parts of the cabinet broken away, showing the mechanism provided for controlling the movement of the side closure member.

Figure 4 is a fragmentary sectional view taken substantially on the line 4—4 of Figure 3.

Figure 5 is a fragmentary sectional view taken substantially along the line 5—5 of Figure 3.

Figure 6 is a fragmentary elevational view, 55

partly in section, showing the side closure member and the mechanism for controlling its movement in their respective positions when the cover is in an open position and the control lever is in a forward operative position.

Figure 7 is a view of a portion of the mechanism of Figure 6 showing the position thereof when the cover is in an open position and the control lever is in a rearward operative position such as for reproducing.

Figure 8 is a fragmentary view taken substantially along the line 8—8 of Figure 6.

Reference being had to Figures 1 and 2, there will be seen a cabinet A containing a phonograph B of the type commonly used commercially for recording and reproducing dictation. The phonograph B has a base plate 1 which supports through suitable upright standards the principal parts of the machine. Such parts comprise a record support or mandrel 2 rotatably mounted in a standard 3 usually integral with the base 1. The spaced standards 4 and 5 are integral with the base 1 and serve to support the longitudinal rods 6 and 7. Carried slidably upon the rods 6 and 7 is a carriage 8. Pivotedly connected to the carriage 8 is an arm 9 (see Figure 6) which carries a feed nut 10 adapted to engage a feed screw 11, this screw being rotatably held by the spaced standards 4 and 5. The feed screw 11 is suitably geared to the mandrel 2 so that rotation of the mandrel, as by any suitable rotatory source of power, will effect a rotation of the feed screw 11. Through the engagement of the feed nut 10 with the feed screw 11 a longitudinal movement, 35 with respect to the mandrel 2, is then imparted to the carriage 8. The arm 9 is suitably coupled to a control lever 12 which is provided for controlling the engagement of the feed nut 10 with the feed screw 11, and for effecting other operative adjustments to the phonograph as are subsequently described.

The mandrel 2 may be of any desirable form for removably holding a cylindrical record C. For convenience of operation there is usually provided a mandrel which is adapted to receive a record from its unsupported end and to hold it tightly thereon after it has reached its operative position. Such a mandrel may typically be of the form described in the United States Patent No. 2,010,717, issued to Heinrich F. Max Gramann on August 6, 1935. This mandrel has a chuck 13 at its outermost end which expands in a radial direction when the record reaches its operative position, thereby holding the record in place. 55 For removing the record therefrom the mandrel is provided with a member 14, at its unsupported end, which is movable inwardly in an axial direction to cause the chuck 13 to contract, thereby releasing the record from the mandrel.

60 The carriage 8 carries a translating device 15 which is adjustable by means of the control lever 12 to an inoperative position or to respective operative positions for recording and reproducing. When adjusted for recording it is adapted to receive sound waves and impart a movement undulating in accordance with those waves to a stylus 16, and, when adjusted for reproducing, to create sound waves in accordance with any undulating movement imparted to a stylus 17, 65 such as by its engagement with a progressive modulated groove on the record C. These sound waves are conveyed to, and away from, the translating device 15 by means of a flexible tubular member 48, or speaking tube, which carries at 70 its far end a hand-piece 49 usable as a mouth-

piece in recording, or as an ear-piece in reproducing.

The adjusting of the translating device 15 is done by means of the control lever 12. When this lever is swung forwardly and rearwardly the respective operative adjustments of recording and reproducing are effected, and in these operative positions the feed nut 10 is brought into engagement with the feed screw 11. In the recording and reproducing positions the stylus 16 and 17 are 10 respectively brought into engagement with the record C carried by the mandrel 2. When the control lever is shifted to a position intermediate of its respective operative positions it places the translating device 15 in an inoperative condition and disengages the feed nut 10 from the feed screw 11. In such inoperative position the respective stylus 16 and 17 of the translating device are each removed from contact with the record. The record may then be freely removed 20 from the mandrel 2. When the control lever 12 is in an operative position, any attempt to mount a record on the mandrel 2, or to remove one therefrom, will cause heavy strain upon delicate parts of the translating device and will in every 25 case cause the record surface to be marred. It is therefore important that a means be provided which will render the mandrel inaccessible so that a record cannot be mounted thereon or removed therefrom, when the translating device is ad- 30 justed to an operative condition. In my invention I provide such means as a feature of my novel and improved closely fitting cabinet structure.

It is to be understood that although I illustrate my cabinet with a simple means for obstructing a single manipulation in the operation of the phonograph, except when a primary control of the phonograph is so adjusted to safely permit such first manipulation, my invention 40 also contemplates the provision of a cabinet having a plurality of means for requiring the proper sequence in the operative manipulations, or adjustments, of a phonograph whenever a plurality of such adjustments are required in the operation of the machine. This, however, is only one of several features of my improved phonograph cabinet, as my invention, in its broader aspects, contemplates a generally improved and closely fitting cabinet structure providing full 45 protection to a phonograph and easy access thereto for its safe and convenient operation. Other cardinal features of my cabinet rest in a novel structural arrangement having a pleasing appearance and providing a high degree of portability and easy access to the phonograph for its 50 servicing or repair.

The frame of my cabinet comprises the respective left and right side sections 18 and 19 forming the central portions of the respective side 55 walls of the cabinet. These sections may be suitably cast in any desirable form, but I prefer that they be arch-shaped and have an increased wall thickness near the rim thereof such as is shown in Figure 1. They may also be desirably provided with recesses at their bottom 60 central portions such as the recess 19' for the section 19, which recesses aid in the lifting of the cabinet from any support provided therefor. The side sections 18 and 19 are rigidly connected together by means of the respective front and rear tie bars 20 and 21. For connecting the tie bars to the side sections there are provided lugs in the rear and front portions of the respective 65 sections, such as the lug 22 on the rear portion 70

of the right hand section 19 shown in Figures 3, 4 and 5. The respective lugs have apertures through which pass suitable screws that thread into the respective tie bars, such as the screw 5 23 for holding the lug 22 to the rear tie bar 21. By this arrangement the side sections 18 and 19 and the tie bars 20 and 21 form the frame of the cabinet and the supporting structure for the phonograph B. The bottom of the cabinet 10 may be closed in any desirable manner.

For securing the phonograph B to the aforesaid supporting structure there are provided in the respective left and right side sections 18 and 19 suitable front and rear bosses such as 24 and 15 25 for the left side section 18, and 26 and 27 for the right side section 19. The base plate 1 of the phonograph is provided with downwardly extending corner posts 28 and 29 on the respective front and rear portions of the lefthand side, and 20 with the posts 30 and 31 on the respective front and rear portions of the right-hand side. The posts 28 and 29 are respectively connected at their lower ends to the bosses 24 and 25, as by the screws 24' and 25'. The posts 30 and 31 25 are similarly secured to the respective bosses 26 and 27, as by the screws 26' and 27'. By this means the base plate 1 is rigidly connected to the frame of the cabinet A. The phonograph B which is supported by the base plate 1 is disposed 30 thereon in such an arrangement as to bring the axis of the mandrel 2 in alignment with the vertical center lines of the side sections 18 and 19.

In my cabinet structure the front and rear portions are respectively enclosed by means of the 25 closure sections 32 and 33. These closure sections have inwardly curving lower portions which rest upon the respective tie bars 20 and 21. These sections may conform to, or lap slightly inwardly of, the respective side sections 18 and 19 so as to 40 complete the enclosure of the ends of the cabinet. They may be of any suitable form for giving a pleasing appearance to the cabinet such, for example, as is illustrated in Figures 1 and 2. They may be respectively fabricated from sheet 45 metal by any suitable means, such as by stampings. The rear section 33 is provided with the respective left and right side portions 33' and 33'' so that it completes the enclosure of the rear half of the cabinet. The front section 32 completes the enclosure of the lower front portion 50 of the cabinet, the remaining portion of the cabinet being enclosed by a cover 34 which is adapted to swing upwardly to a position above the rear closure section 33 and to conform to the upper portion thereof. For this reason the left and right side portions 33' and 33'' of the rear closure section 33 are extended into the front half of the cabinet and provided along their edges 34' with a curvature which is identical to the curvature of 55 that upper portion of the section 33 to which the cover 34 conforms when it rests in its open position.

The front and rear closure sections 32 and 33 are each detachably connected to the frame of the cabinet to provide easy access to the phonograph for its servicing or repairs. For holding the rear closure section 33 in place it is provided near the bottom thereof with the respective left and right side arms 35 and 36 (see Figure 6) which are suitably secured thereto as by welding. The forward portions of the respective arms 35 and 36 are provided with downwardly extending notches, such as 36' for the arm 36, which are adapted to engage with the respective outwardly extending pins 37 and 38 provided on

the respective bosses 25 and 27. The closure section 33 is suitably secured to the frame of the cabinet at its upper end by means of the respective screws 39 and 40, shown in Figures 1 and 4 respectively, which thread into the arched rim 5 portions of the side sections 18 and 19 for respectively holding the left side portion 33' to the section 18 and the right side portion 33'' to the section 19. Thus with the removal of the screws 39 and 40 the rear closure section 33 tips backwardly for easy detachment from the frame of the cabinet. 10

For detachably connecting the front closure section 32 to the frame of the cabinet, this section is provided with respective left and right 15 side arms, such as the arm 41 on the righthand side, which arms are suitably secured thereto as by welding. These left and right side arms are in all respects similar to the arms 35 and 36 of the rear closure section 33, and are adapted 20 to engage with the respective outwardly extending pins 42 and 43 provided on the respective bosses 24 and 26. This closure section 32 is provided with forwardly extending ears at its upper left and right sides, such as the ear 44 on 25 the righthand side shown in Figure 2. Extending respectively through these ears, as by suitable apertures provided therein, are the screws 45 and 46 which thread into the respective left and right side sections 18 and 19 for holding the upper 30 portion of the closure section 32 in place. Thus, the front closure section 32, as in the case of the rear closure section 33, is readily detachable from the frame of the cabinet.

As shown in Figures 1 and 2 the front closure 35 section 32 extends forwardly at the front portion of the phonograph B to provide a compartment 47 which serves for conveniently holding the tubular member 48 and handpiece 49, as during periods of non-use. During the use of the 40 phonograph the tube 48 may be left to extend outwardly of the cabinet. In this case there may be provided a suitable member, not shown, which may be moved outwardly of the cabinet for supporting the handpiece 49 during inoperative 45 periods in the use of the machine. When the cabinet A is to be closed the tube 48 may be disposed within the compartment 47 lengthwise thereof and the handpiece 49 may be disposed in any desirable upright position such, for example, 50 as is shown in Figures 1 and 2.

In order to permit access to the record support or mandrel 2 for installing a record thereon, or removing a record therefrom, there is provided an opening 50, preferably circular in form, 55 in the upper arched portion of the righthand side section 19. I prefer that the center of the opening 50 coincide with the axis of the mandrel 2 and that the diameter of the opening be suitably larger than the diameter of the record C so that 60 the record may be conveniently installed on or removed from the mandrel 2. For this opening there is provided a side closure member 51 having an upper circular portion conforming to the opening 50 and movable between open and closed 65 positions. The closure member 51 may be moved in any desirable manner but I preferably have it slide upwardly and downwardly in the grooves 52 provided in the vertical rim portion of the side section 19. These grooves are disposed in the 70 rim adjacent to the center panel portion 53 so that the closure member 51 fits closely thereto. In my invention the movement of the closure member 51 is controlled both by the cover 34 and the control lever 12 in a novel manner for facili- 75

tating and safeguarding the operation of the phonograph.

For completing the enclosure of the cabinet there is provided the cover 34 having a handle 54. This cover is adapted, when in a closed position, to form an upward extension of the walls of the front closure section 32 and to conform with the edges 34' of the rear closure section 33. The general shape of the cover 34 may be such 10 as to give the cabinet a symmetrical appearance from the end when the cover is in a closed position, such, for example, as is shown in Figure 2. The opening 50 is made continuous with the front opening of the cabinet in order to provide the 15 operator with full visibility of the mandrel 2, thereby facilitating the mounting of a record thereon or its removal therefrom. In order to provide such continuity a segment 55 of the arched rim portion of the side section 19 is broken 20 away; it may be secured to the cover 34, as shown in Figure 1, so that it comes into a position completing the arch of the section 19 when the cover is in a closed position. On the corresponding portion of the opposite side the cover laps inwardly of the forward arched portion of the left side section 18.

The cover 34 swings upwardly in a novel manner to a position above the cabinet wherein it conforms with the upper portion of the rear closure section 33 as shown in Figure 1. The pivoting arrangement for securing such upward swinging movement comprises the respective left and right side levers 56 and 57 pivoted on studs secured, as by riveting or welding, to the respective left and right side walls of the rear closure section 33, such as the pivot stud 58 for the right hand side. The cover 34 is provided with L-shaped side extensions 59 and 60 on its respective left and right sides, which extensions are 40 pivotally connected at points suitably in from the ends thereof to the respective side levers 56 and 57 as by the pivots 56' and 57'.

For guiding the movement of the cover 34 between its open and closed positions there are 45 provided the respective left and right tracks 61 and 62 which are secured at their respective rear end portions 61' and 62', to the respective left and right side walls 33' and 33'' of the rear closure section 33, as by welding. These respective rear end portions are suitably offset so that the respective tracks 61 and 62 may extend along the sidewalls 33' and 33'' with suitable clearance. These tracks curve downwardly substantially in 50 an arc about the pivot studs provided for connecting the side levers 56 and 57 to the side walls of the rear closure section 33, such as the pivot stud 58 on the right-hand side. There are secured at the ends of the side extensions 59 and 60 inwardly extending pins 63 and 64 which carry 55 the respective rollers 65 and 66. These rollers ride on the respective tracks 61 and 62 for guiding the movement of the cover 34. In order to maintain the rollers in engagement with their respective tracks there are provided the tension springs 67 and 68 which respectively connect the pin 63 with the lower end of the side lever 56 and the pin 64 with the lower end of the side lever 57. For this reason the side levers 56 and 57 have their lower end portions bent inwardly and 60 respectively provided with suitable apertures through which may hook the respective springs 67 and 68, such as the end portion 57'' for the lever 57.

At the rear of the respective tracks 61 and 62 75 there are provided suitable notches 69 and 70 de-

fining the open position of the cover 34, as shown in Figures 1 and 2 respectively. As the cover moves downwardly from such open position it will first tilt forwardly about the pivots 56' and 57' as the rollers 65 and 66 move out of the respective notches 69 and 70. Such initial forward tilting movement of the cover as it moves from its open position prevents any rubbing between the cover and the upper portion of the rear closure section 33. Likewise, in the upward movement of the cover it will swing above the rear closure section with suitable clearance and then tilt rearwardly to its aforesaid open position as the rollers 65 and 66 register with the respective notches 69 and 70. By this novel hinging arrangement of the cover 34 I am enabled to move the cover to an open position closely fitting the cabinet and yet expose the entire front portion of the phonograph for its convenient operation with the use of a very small and shallow cover. 20

In the cabinet of my invention the side closure member 51 is coupled to the cover 34 so that upward and downward movements of the cover 34 will effect respective downward and upward movements of the side closure member 51. The closure member 51 is preferably also suitably coupled to the control lever 12 so that the member 51 will move to a position obstructing the accessibility of the mandrel 2 whenever the control lever is moved to an operative position. By 30 this novel arrangement I secure the following desirable actions: With the control lever 12 in an inoperative position, as the cover 34 is moved between its open and closed positions the side closure member 51 is moved between its respective fully open and closed positions. With the control lever 12 in an operative position, as the cover 34 is moved between its closed and open positions the side closure member 51 is respectively moved between its closed and a suitable intermediate position. With the cover 34 in an open position, as the control lever 12 is moved between its operative and inoperative positions the side closure member 51 is moved between its respective intermediate and fully open positions. Thus, 40 my cabinet completely encloses the phonograph and yet provides ready access thereto for its convenient operation, such access being controlled in a manner to safeguard the phonograph as it is used. The mechanism coupling the cover 34 and control lever 12 with the closure member 51 to effect such results will now be described in detail. 45

The mechanism coupling the cover 34 with the closure member 51 comprises a vertically disposed link member 71 shown clearly in Figures 3 and 6. 55 This link member is pivotally connected at its upper end, as by the pivot 72, to the lower end of the side lever 57. The lower end of the link has an enlarged portion 71' within which is provided a cam slot 73. This slot is preferably arc 60 shaped about the pivot 72 at its forward and rearward end portions, and is curved upwardly from its forward end in a suitable manner, such as is shown in Figure 3. At the lower righthand side of the cabinet there is provided a side arm 74 65 which is pivoted to the righthand arm 36 provided for holding the rear closure section 33 in place. The arm 74 carries an inwardly extending pin or roller 75 at a position approximately midway of its ends. The roller 75 registers with the 70 cam slot 73 and may be normally retained in the forward end of this slot by reason of a light tension spring 76 connected between the lower end portion 71' of the link member 71 and the rear portion of the arm 36. The forward end portion 75

74' of the arm 74 is provided with a longitudinal slot 77. In this slot there slidably engages an inwardly extending pin 78 secured to the lower mid-portion of the closure member 51. Downward or closing movement of the cover 34 rotates the side lever 57 in a counterclockwise direction. This causes the link member 71 to be raised, and therefore the arm 74 is rotated in a clockwise direction to move the closure member 51 upwardly. The length of the various members comprising this coupling mechanism, and the location of the various pivots, are chosen so that the closure member 51 is in its open or most downward position when the cover 34 is fully open, and so that the member 51 has reached its closed or most upward position when the cover 34 is fully closed. It is thus obvious that a movement of the cover 34 between its open and closed positions effects a movement of the closure member 51 between its respective open and closed positions.

As aforementioned, with the cover 34 in its open position, as the control lever 12 is moved to either of its operative positions, the side closure member 51 is moved upwardly to a partially closed position, such, for example, as shown in Figure 1. Normally the control lever 12 pivots about the longitudinal rod 6 and slides thereon as the carriage 2 moves longitudinally of the mandrel 2. For coupling the control lever 12 with the closure member 51, the control lever 12 is keyed or splined to the rod 6 as shown in Figure 3. This spline connection may comprise a screw 79 threading into the hub 12' of the control lever 12 and engaging with a longitudinal slot or groove 6' cut into the rod 6. The control lever 12 is then rotatably coupled to the rod 6 and may slide longitudinally thereon, the rod 6 being pivotally supported at its ends in the left and right standards 4 and 5 in any suitable manner. As may be seen clearly in Figures 3, 6 and 7 a cam plate 80 is provided on the righthand end of the rod 6. For securing the cam plate thereon the end portion of the rod 6 is provided with a reduced diameter portion 6" to form a shoulder on the rod. The cam plate is apertured to fit the portion 6" and is provided with a tongue 81 engaging with the groove 6', the cam plate being suitably held against the shoulder above-mentioned by means of a screw 82 threading lengthwise into the rod 6.

The link member 71 extends upwardly of the pivot 72 and is provided at the upper end thereof with a pin or roller 83—which registers with the surface of the cam plate 80. The cam plate 80 has a central concavely shaped portion 84, and is positioned on the rod 6 with respect to the control lever 12 so that the roller 83 engages with the central point of the concavely shaped portion 84 when this lever is in a central or inoperative position and the cover 34 is in an open position, such as is shown in Figure 3. As the control lever 12 is moved to either of its operative positions such, for example, as its forward position for recording and its rearward position for reproducing, the cam plate 80, by its engagement with the roller 83, will rotate the link member 71 in a clockwise direction about its pivot 72. By reason of the upwardly curving cam slot 73, provided in the lower end portion 71' of the link 71, a clockwise rotation of the link member 71 produces a clockwise rotation of the arm 74 to move the closure member 51 upwardly to a position such as shown in Figure 1. If the control lever 12 is moved forwardly to its usual position for recording the mechanism coupling the control lever to the closure member 51 takes the position

shown in Figure 6. If the control lever 12 is moved rearwardly to its usual position for reproducing the mechanism takes the position shown in Figure 7. In each case the closure member 51 is moved upwardly to a partially closed position 5 so as to make the mandrel inaccessible for mounting a record thereon, or removing a record therefrom.

In order that a return movement of the control lever 12 from either of its operative positions to its inoperative position may effect a downward movement of the closure member 51 to its fully open position, the outline of the cam 80 is closed, except over its central portion, by means of a guide member 85 secured to the cam plate 80 by the rivets 86. The guide member 85 is in the form of a plate having inwardly extending ribs 86 and 87 which conform in curvature to that portion of the cam 80 to which they are adjacent. The roller 75 thus registers with the inward surface of the ribs 86 and 87 as the control lever is swung to its inoperative position from either of its operative positions, thereby imparting a counterclockwise rotation to the link member 71. The cam 80 is, however, not closed over its end portions 88 and 89, and over the central portion 84, in order that the roller 75 may be free to leave the cam at these points, such as is necessary whenever the cover 34 is swung downwardly to a closed position. The end portions 88 and 89 30 and the central portion 84 of the cam 80 are substantially arc shaped about the pivoting axis of the cam 80 in order that the roller 75 will not tend to leave the cam 80 at these positions except as an incident of downward movement of the 35 cover.

It will be observed from Figure 3 that the side closure member 51 rests in its open position when the cover 34 is in an open position and the roller 75 of the pivoted arm 74 registers with the forward end of the cam slot 73. With the roller 75 maintaining this forward position in the cam slot 73, a movement of the cover 34 to its closed position will effect a movement of the closure member 51 to its fully closed position. Such closing movement of the cover 34 causes the roller 83 of the link member 71 to move through the locus 91 to a position 92 shown in Figure 3. However, when the cover 34 is open and the control lever 12 is in either of its operative positions the roller 75 registers with the rear end of the cam slot 73, and the roller 83 has the position indicated at 93. Therefore, in order to provide a free closing of the cover 34 when the control lever is in an operative position, some means must be provided for rotating the link member 71 in a counterclockwise direction simultaneously with the closing of the cover so that the roller 75 will move forwardly in the cam slot 73 and register with the forward end thereof when the cover reaches its 60 closed position. The roller 83 will then have moved through a locus to a position coinciding with the position 92. For effecting such counterclockwise rotation of the link member 71 I provide a suitably shaped stationary guide member 94 65 which is secured to the righthand side wall 33" of the rear closure section 33, as by rivets or welding. As the cover 34 is closed with the control lever 12 in either of its operative positions, the roller 83 leaves the cam 80 and registers with the guide member 94 which guides it to the position 92.

If the cover 34 is opened when the control lever 12 is in either of its operative positions, the link member 71 must be rotated in a clockwise direc- 75

tion with such opening movement so that the roller 75 will register with the rearward end of the cam slot 73 when the cover reaches its open position. The roller 83 will then have to return 5 through a suitable locus from the position 92 to the position 93. When the control lever 12 is in its rearward operative position the roller may be easily guided to the position 93 by an extension of the upward end portion 88 of the cam 80, as 10 is clearly shown in Figure 7. For guiding the roller 83 to the position 93 when the control lever is in its forward operative position I provide a suitably shaped extension 87' on the lower end portion of the rib 87, as is shown in Figure 6.

15 Although I have described a preferred embodiment of my invention it is to be understood that the same is subject to many changes and modifications without departure from the scope of my invention which I now undertake to express 20 according to the following claims.

I claim:

1. In a cabinet containing a phonograph and having open front and side portions for exposing respectively adjacent manipulative parts of said 25 phonograph: movable closure means for said front portion; a slidably movable closure means for said side portion; and means for operating one of said closure means as an incident of operating the other.

30 2. A cabinet containing a phonograph and having two closure members movable to respective open positions for rendering said phonograph accessible for operation, one of said closure members being movable outwardly of said cabinet, and 35 the other of said closure members being movable within said cabinet; and means, operatively connecting said closure members together, for opening one of the closure members as an incident of opening the other.

40 3. In a cabinet containing a phonograph: a front cover pivoted to swing outwardly from said cabinet; a side closure member slidably movable along a side wall of said cabinet for exposing a portion of said phonograph; and means, operated by the outward swinging movement of said cover, 45 for slidably moving said closure member to expose said portion of the phonograph.

4. In a cabinet for a phonograph: a cover pivoted to swing upwardly and downwardly for respectively opening and closing a front portion 50 of said cabinet; a side closure member slidably movable for opening and closing a side portion of said cabinet; and means, connecting said side member with said cover, for opening and closing said side closure member as said cover is respectively opened and closed.

55 5. A cabinet containing a phonograph and comprising two closure members, one of said closure members being located above a portion of said cabinet and pivoted to swing downwardly for preventing access to a front portion of said phonograph, the other of said closure members being movable along the side of said cabinet for preventing access to a manipulative part on the side of said phonograph; and means, connecting 60 said first member with said second member, for rendering said manipulative part inaccessible as said front portion is rendered inaccessible.

6. In a cabinet containing a phonograph: a 70 front cover pivoted to swing upwardly to a position above the rear portion of said cabinet; a side closure member movable downwardly for exposing an end portion of said phonograph; and means for moving said side member downwardly 75 with the upward movement of said cover.

7. A cabinet for a phonograph comprising a phonograph-supporting frame having portions forming side sections of the cabinet, other cabinet side sections detachably connected to said frame, and a movably mounted cover completing the 5 enclosure of the cabinet.

8. A cabinet for a phonograph comprising a phonograph-supporting frame having extensions forming central portions of the ends of said cabinet, a front section completing the enclosure 10 of the lower front portion of said cabinet, a rear section substantially completing the enclosure of the rear half of said cabinet, said rear sections having side portions extending forwardly above said central end portions and terminating along 15 an edge having a curvature substantially conforming to that of the upper portion of said rear section, and a cover completing the enclosure of said cabinet and pivoted to swing to an open position wherein it conforms with said upper 20 portion to form an upward extension of the side walls of said rear section.

9. A cabinet containing a phonograph having a mandrel rotatably supported at one end and free at the other for receiving a record, said cabinet comprising a phonograph supporting frame having extensions forming side wall sections thereof, one of said sections having an opening exposing the free end of said mandrel, a rear wall section detachably connected to said frame, a 25 front wall section detachably connected to said frame and forming a compartment forwardly of said phonograph, and a cover movably mounted for opening and closing movement thereof.

10. A cabinet for a phonograph having rotatable means for supporting a record, said cabinet comprising a supporting frame forming side wall sections thereof, one of said sections having an opening providing access to said means for mounting a record thereon, front and rear wall sections detachably connected to said frame, and 40 a movably mounted cover substantially completing the enclosure of said phonograph.

11. In a cabinet containing a phonograph which has a control member movable into operative and inoperative positions: a closure member 45 movable between open and closed positions; and means, connecting said closure member with said control member, for effecting movement of said closure member as said control member is moved into operative and inoperative positions.

12. In a cabinet containing a phonograph which has a control lever movable from a neutral position to operative positions respectively adjusting said phonograph for recording and reproducing; means for exposing a part of said phonograph on which manipulations are performed in the operation thereof, said means comprising a closure member movable between closed and open positions; and means, connecting said control lever with said closure member, for moving said member to a partially closed position as said control lever is moved to either of said operative positions.

13. In a cabinet containing a phonograph which has a control lever movable from a neutral 65 position to operative positions respectively adjusting said phonograph for recording and reproducing: a side closure member movable to an open position to expose for operation an end portion of said phonograph; and means, connecting said control lever with said member, for moving said member to a position to render said end portion inaccessible for operation as said control lever is moved to either of said operative positions.

14. A cabinet containing a phonograph and having a side closure member movable from a position obstructing the operation of a manipulative part of said phonograph, to an open position; a control lever for said phonograph movable to operative and inoperative positions; and means, connecting said control lever with said member, for moving said member to said open position as said control lever is moved to said inoperative positions. 5
15. In a cabinet containing a phonograph having a control member movable into operative and inoperative positions: a cover movable between open and closed positions; a side closure member movable between open and closed positions; means for moving said side closure member as an incident of moving said cover; and means, operated incidental to the movement of said control member, for moving said side closure member 10 when said cover is open. 15
16. In a cabinet containing a phonograph which has a control member movable into operative and inoperative positions: a cover movable between open and closed positions; a side closure member movable between open and closed positions; means for moving said side closure member as an incident of moving said cover; and means, connecting said side closure member with said control member, for moving said side closure member through a portion of its travel as said control member is moved into operative and inoperative positions. 20
17. In a cabinet containing a phonograph which has a control lever movable to operative and inoperative positions: a cover pivoted to swing downwardly for closing movement thereof; means for exposing a manipulative part of said phonograph, comprising a side closure member movable between open and closed positions; means, connecting said control lever with said member, for moving said member to a position intermediate of said open and closed positions as said control lever is moved to operative position; and means, connecting said cover with said member, for moving said member to a closed position as said cover is swung downwardly. 30
18. In a cabinet containing a phonograph having a control lever for adjusting its operation and a support for rotating a record: a cover pivoted to swing downwardly for closing movement thereof; a side section having an opening providing operative access to said support for mounting the record thereon and removing the record therefrom; means, operated by said control lever, for partially closing said opening; and means, operated by said cover, for fully closing said opening. 40
19. In a cabinet containing a phonograph which has a control lever movable to operative and inoperative positions: a cover pivoted to swing downwardly for closing movement thereof; a side section having an opening which exposes a manipulative part of said phonograph; means for partially closing said opening as said control lever is moved to said operative positions; and means for fully closing said opening as said cover is swung downwardly. 50
20. In a cabinet containing a phonograph which has a control lever movable to operative and inoperative positions: a cover pivoted to swing upwardly to an open position and downwardly therefrom; a side section having an open- 55
- ing which exposes a part for manipulation in the operation of said phonograph; a member movable between closed and open positions for said opening; means, operated by said cover, for moving said member between said closed and open positions; and means, operated by said control lever, for moving said member through a portion of the distance between said positions when said cover is open. 60
21. In a cabinet containing a phonograph which has a control lever for adjusting the operation of said phonograph: a cover pivoted to swing upwardly and downwardly; a side section having an opening exposing a part for manipulation in the operation of said phonograph; a movable member for said opening; means, operated by said control lever, for moving said member to a position to obstruct the manipulation of said part; and means, operated by said cover, for moving said member to a position to close 20 said opening. 65
22. In a cabinet containing a phonograph which has a control lever movable to operative and inoperative positions: a cover pivoted to swing upwardly for exposing a manipulative portion of said phonograph; a side section having an opening for exposing another manipulative portion of said phonograph; a member movable between open and closed positions for said opening; means, operated by said cover, for moving said member between said positions when said control lever is in said inoperative position, and for moving said member through a portion of the distance between said positions when said control lever is in said operative position. 30
23. In a cabinet containing a phonograph comprising a record support and a control lever movable to operative and inoperative positions: a cover pivoted to swing upwardly to permit access to said control lever; a movable member for rendering said record support operatively accessible; and means, operated by said cover, for moving said member to render said record support operatively accessible when said control lever is in inoperative position. 35
24. In a cabinet containing a phonograph comprising a control member movable to operative and inoperative positions and a mandrel rotatably supported at one end and free at the other for receiving a record: a cover pivoted to swing to open and closed positions; a side section having an opening exposing the free end of said mandrel; a movable closure member for said opening; means, operated by said control lever, for moving said member to a partially closed position when said cover is in said open position; and means, operated by said cover, for moving said member between its partially closed and fully closed positions when said control lever is in said operative position. 40
25. In a cabinet containing a phonograph which has a control lever adjustable to operative and inoperative positions: a cover pivoted to swing upwardly for exposing said control lever; a member movable for exposing a manipulative portion of said phonograph; means for moving said member in one direction with upward movement of said cover; and means, operated by said control lever, for moving said member in the opposite direction when said cover is in said upward position. 50

LOUIS Z. LA FOREST.
